UNITED STATES PATENT OFFICE.

WILHELM VASSEN, OF AACHEN-FOEST, GERMANY.

METHOD OF ROLLING PROFILE IRON WITH PARALLEL FLANGES.

1,068,467.

Specification of Letters Patent.

Patented July 29, 1913.

Application filed February 14, 1912. Serial No. 677,589.

To all whom it may concern:

Be it known that I, WILHELM VASSEN, a subject of the Emperor of Germany, and residing at Stumpergasse 42, Aachen-Forst, Germany, have invented a certain new and useful Method of Rolling Profile Iron with Parallel Flanges, of which the following is a specification.

This invention relates to a method of rolling profile iron with parallel flanges, and to machinery for carrying out the said method.

The present invention is an improvement in the method described in the specification of my prior Letters Patent No. 1,025,078, in which profile iron is rolled with parallel flanges which are flat throughout the process, so that it is not possible to allow the rollers for treating the edges of the flanges to press thereon with any desired pressure; on the contrary the pressure to be exerted must be proportional to the stability of the material to be rolled just as is customary in connection with universal rolling mills for flat iron bars.

According to the present method the flanges are given a slight curvature during the preliminary rolling, so that the rolls for treating the flange edges can press with considerable pressure thereon without fear of any unintentional bending taking place, whereby the edges, which were previously rounded, are now flattened, while the flanges may also be shortened, if necessary.

In the drawings, Figures 1, 2, 3, and 4 illustrate the shape of the several sets of rolls through which the bar to be rolled passes.

Fig. 1 of the drawings shows the shape of the rollers of a four roll mill through which a blank consisting of a block of rectangular cross section is passed and is thereby given a cross section in which the flanges are inclined to each other at an acute angle while they are at the same time bent. The rolling faces *a* and *b* of the horizontal rollers A and B are concave in profile, while the rolling faces *c* and *d* of the vertical rolls C and D are convex in profile, so that the flanges are bent in the manner clearly shown in the drawing.

Fig. 2 shows the following set of rolls which are arranged in the same way as the previous set except that the pass is of such a shape as to increase the angle between the flanges, the curvature of the flanges being, of course, retained.

Fig. 3 shows the rolls for treating the edges of the flanges. These rolls consist of a central part *e* and side extensions *f* and *g*, the rolling faces *h* of the part *e* being concave so as to correspond to the curvature of the flanges. The parts *f* are provided with rolling faces *k* which are approximately at right angles to the flanges and have a width equal to the maximum desired thickness of 60 flange, while the parts *g* are provided with faces *m* which project beyond the parts *f* and are inclined at an acute angle to the flanges. Owing to the curvature of the flanges, considerable pressure may be exerted thereon, so that their rounded edges are flattened, while the parts *g* prevent any slipping or bending of the flanges when the pressure is excessive, and, at the same time, serve as a guide for the bar. It is also possible by this method to make the flanges 65 narrower by exerting a very heavy pressure 70 on the edges, the peculiar construction of the rolls preventing any bending.

Fig. 4 represents the finishing rolls, consisting of horizontal cylindrical rolls *n* and vertical cylindrical rolls *p*. In this set of rolls the flanges are straightened and the bar finished.

The general construction and arrangement of these rolls and the means for adjustment may be the same as is described in the specification of my prior Letters Patent referred to above.

Having now described my invention what I claim as new and desire to secure by Letter Patent is:—

1. In a method of rolling profile iron with parallel flanges, passing a blank consisting of a block of rectangular cross section 95 through a set of four rolls in which the block is given a cross section with flanges inclined to each other at an acute angle and slightly bent, passing the bar through a second similar set of rolls in which the 100 flanges are flattened out to form an obtuse angle, the curvature of the flanges being retained, operating with heavy pressure upon the edges of the bent flanges in a set of two rolls, and straightening out the flanges and 105 finishing the bar in a set of four rolls with cylindrical surfaces.

2. In a rolling mill for rolling profile iron with parallel flanges, a set of four rolls comprising a pair of horizontal rolls having 110 concave rolling faces, and a pair of vertical rolls having convex rolling faces.

3. In a rolling mill for rolling profile iron with parallel flanges, a set of two rolls each comprising a central portion having concave rolling faces, undercut rolling faces 5 projecting from each side of said central portion for operating upon the flange edges and arranged approximately at right angles to said flanges, and a guiding face project-

ing beyond each undercut rolling face and inclined at an acute angle to the flanges.

In testimony whereof I affix my signature in presence of two witnesses.

WILHELM VASSEN.
